(57) **CLAIM**

The ornamental design for a connector of lightening arrester wires for lightning arrester equipment, as shown and described.

DESCRIPTION

FIG. 1 is a top and front perspective view of connector of lightening arrester wires for lightning arrester equipment showing my new design;
FIG. 2 is a front side view thereof;
FIG. 3 is a rear side view thereof;
FIG. 4 is a left side view thereof;
FIG. 5 is a right side view thereof;
FIG. 6 is a top view thereof;
FIG. 7 is a bottom view thereof; and,
FIG. 8 is a bottom and front perspective view thereof, in use condition.
